FASTENING MEANS FOR AIRSHIP ENVELOPES

Filed March 28, 1929

UNITED STATES PATENT OFFICE

KARL ARNSTEIN, PAUL HELMA, AND KURT BAUCH, OF AKRON, OHIO, ASSIGNEES TO GOODYEAR-ZEPPELIN CORPORATION, OF AKRON, OHIO, A CORPORATION OF DELAWARE

FASTENING MEANS FOR AIRSHIP ENVELOPES

Application filed March 28, 1929. Serial No. 350,567.

This invention relates to envelopes for airships, and it has particular relation to fastening devices employed in securing the outer envelopes or covers to the framework of rigid airships.

One object of the invention is to provide an envelope which is secured to the framework in such manner that it is maintained in substantially taut condition and is prevented from flapping.

Another object of the invention is to provide connecting elements for tautening the outer envelopes of airships between the structural elements which support such envelopes.

In order to maintain a minimum resistance to air on the surface of airships, it is essential that the envelope be maintained taut and be prevented from movement, such as flapping. Heretofore, portions of the

outer envelope were constructed in the form of gores of considerable width that were applied to the airship hull structure and drawn manually until the envelope was taut. Thereafter, several coatings of dope were applied which contracted the envelope until it was reasonably taut, but even this treatment did not entirely prevent it from flapping.

The portions of the outer envelope extending between adjacent longitudinals and normally having plane surfaces always have a tendency to flap despite the fact that the envelope has been stretched under considerable tension. According to this invention, the outer envelope covering the panels between the longitudinals is drawn inwardly by means of devices including strips of material in the form of catenaries that have adjustable connections adjacent accessible parts of the airship whereby the envelope may be drawn inwardly and at such locations as to insure the minimum amount of movement of the fabric.

For a better understanding of the invention, reference may now be had to the accompanying drawings, forming a part of the specification, of which;

Figure 1 is a fragmentary cross-sectional view of a portion of an airship having an outer envelope connected thereto according to the invention;

Figure 2 is a fragmentary cross-sectional view substantially at right angles to that shown in Figure 1;

Figure 3 is a fragmentary cross-sectional view illustrating a form of the invention 55 slightly different from that shown by Figure 2;

Figure 4 is a cross-sectional view taken substantially along the line IV—IV of Figure 1;

Figure 5 is a cross-sectional view on a larger scale, taken substantially along the line V—V of Figure 1;

Figure 6 is a fragmentary view of the inner part of an airship in which constructions embodying the invention are installed; 65

Figure 7 is a cross-sectional view taken substantially along the line VII—VII of Figure 6;

Figure 8 is a fragmentary cross-sectional 70 view showing in detail certain features of the construction; and

Figure 9 is a cross-sectional view showing another form of loop employed in practicing the invention. 75

Referring to Figures 1, 2 and 3, portions of main rings 10, auxiliary rings 11 and longitudinals 12 of an airship are shown diagrammatically and serve to support an outer envelope or cover 13 composed of flexible material such as fabric. Each portion of the envelope covering the panel defined by the longitudinals 12 and rings 10 and 11 in its normal position is taut, as indicated by the broken lines 14 shown in Figures 2 and 3. 80

Strips of fabric 15 are secured to the inner surface of the envelope by suitable means, such as stitching or cementing, indicated at 16 and 17. These strips of fabric are constructed substantially in the form of catenaries, and the free edge of each is folded and secured, as indicated at 18 in Figure 5, for the purpose of providing openings or looped portions 19 in which a cord or wire 20 is slidably disposed. As best shown by Figure 9, both edges of the fabric strip 15 can be secured to the envelope 13, thereby forming the loop 19. The ends of the wire are connected, as indicated at 22, to an accessible portion of the airship superstructure, such as the 95 100

main rings 10, and turn-buckles 23 serve to tension the wires, thereby tending to straighten them and to draw the envelope 13 inwardly to the position indicated by the full lines of Figures 2 and 3. A portion of the strip 15 is cut away, as indicated at 24, to expose the wire 20, and the exposed portion of the wire is detachably and slidably secured through eyelets or hooks 25 mounted upon the rings 11. Other eyelets or hooks 26 are located on the main rings 10. From this construction it will be observed that the entire portion of the envelope extending from one main ring to another between adjacent longitudinals 15 can be drawn inwardly and thus tightened by manipulating the turn-buckles 23.

One or more of the strips 15 may be employed according to the requirements with reference to the distance between adjacent longitudinals. Two of these strips are shown in Figure 3. Preferably, the wires are inserted through the openings 19 of the strips before the gores constituting the envelope are attached to the framework of the airship. Then the wires are attached to the hooks 25 and 26, and fastened at their ends, as described above. After the envelope has been applied in relatively taut condition, such as that indicated by the broken lines of Figures 2 and 3, the wires are tensioned by manipulating the turn-buckles to draw the envelope inwardly to the position shown in full lines of Figures 2 and 3.

Another form of the invention illustrated by Figures 6, 7 and 8 includes strips of fabric 30 in the form of catenaries having connections 31, such as stitching, to the envelope 13. These catenaries preferably extend longitudinally of the airship. One edge portion of each of the catenaries is provided with a cord or wire 32 that is disposed through a loop 33 therein. At spaced points 34, connections 35 to the longitudinals are provided, each of which connections includes a turn-buckle 36. In order that the connections 35 may be hooked upon the wires 32, the latter are exposed adjacent the points 34. Each of the connections 35 is attached separately to the longitudinals of the airship, and the outer envelope is thereby drawn inwardly by a series of separately adjustable devices.

From the foregoing description, it will be apparent that the tendency of the portions of the airship to flap is reduced to a minimum, and that the means for maintaining the envelope in a taut condition uniformly distributes the stresses throughout the portions thereof upon which the connections are secured.

Although we have illustrated only the preferred forms which the invention may assume and have described those forms in detail, it will be apparent to those skilled in the art that the invention is not so limited, but that various modifications may be made

therein without departing from the spirit of the invention or from the scope of the appended claims.

What we claim is:

1. In an airship having a rigid framework and an envelope secured thereon, a strip of flexible material having one edge portion thereof secured to the envelope, said strip of material varying in width, and a tension member secured to the other edge portion of the strip and to the framework, said tension member exerting forces transversely of the cover. 70

2. In an airship having a rigid framework and an outer cover secured thereon, a strip of flexible material having a looped portion, said looped portion varying in distance from the envelope, a tension member disposed through the looped portion and means for securing the tension member to the framework. 80 75

3. In an airship including a rigid framework and an outer envelope secured thereon, an elongate flexible member connected at a plurality of points to the framework, means for connecting the flexible member to the envelope, portions of the flexible member being held nearer the envelope than those portions adjacent said points, and means for tensioning the flexible member to draw the envelope inwardly. 90 85 95

4. In an airship including rings, longitudinals and an outer envelope secured thereon, a strip of flexible material of catenary form secured to the envelope longitudinally of the airship, a tension member connected along the strip of material adjacent one edge thereof, means for connecting a continuous length of the tension member to a plurality of the rings, said means including a device for adjusting the tension member, and means for detachably connecting the tension member to a plurality of the rings. 100 105

5. In an airship including rings, longitudinals and an envelope secured thereon, a strip of flexible material having looped portions disposed longitudinally of the airship and secured to the inner surface of the envelope, said looped portions being spaced from the envelope, said looped portions also being in the form of catenaries, a tension member disposed through the looped portions and connected in a continuous length to a plurality of the rings, hooks fastened to the rings for receiving portions of the tension member, and means for tightening the tension member to draw the envelope inwardly. 110 115 120

In witness whereof, we have hereunto signed our names.

Signed at Akron, in the county of Summit and State of Ohio this 26th day of March, 1929. 125
